UNITED STATES PATENT OFFICE.

CHARLES H. BARTOW, OF LANCASTER, OHIO.

DESIGN FOR A RANGE.

Application filed September 29, 1925. Serial No. 14,945. Term of patent 7 years.

To all whom it may concern:

Be it known that I, CHARLES H. BARTOW, a citizen of the United States, residing at Lancaster, in the county of Fairfield and State of Ohio, have invented a new, original, and ornamental Design for Ranges, of which the following is a specification, reference being had to the accompanying drawing, forming part thereof.

The figure is a perspective view of a range, showing my new design.

I claim:

The ornamental design for a range, as shown.

CHARLES H. BARTOW.
